ATTORNEY.

UNITED STATES PATENT OFFICE.

HARRY G. SLINGLUFF, OF MOUNT VERNON, OHIO, ASSIGNOR TO PITTSBURGH PLATE GLASS COMPANY, OF PITTSBURGH, PENNSYLVANIA, A CORPORATION OF PENNSYLVANIA.

APPARATUS FOR DRAWING GLASS.

1,203,423.

Specification of Letters Patent. Patented Oct. 31, 1916.

Application filed November 1, 1912, Serial No. 729,080. Renewed April 7, 1916. Serial No. 89,725.

To all whom it may concern:

Be it known that I, HARRY G. SLINGLUFF, a citizen of the United States, residing at Mount Vernon, in the county of Knox and State of Ohio, my post-office address being the same, pray that Letters Patent may be granted to me for the new and useful Improvements in Apparatus for Drawing Glass, of which the following is a specification.

This invention has reference to the provision of an improved apparatus such as is used in connection with the drawing of glass cylinders in the manufacture of window glass. The first of the objects of my present invention is the construction of apparatus of the character specified in which the bad effects of uneven temperature on different sides of the cylinder are automatically obviated. In the drawing of cylinders from so-called deep furnace extensions which project at one end of the main furnace, it is found that the heat of the main furnace will interfere with the uniformity of production on opposite sides of the cylinder because that side of the cylinder being drawn which is nearest the body of the furnace will generally be exposed to a greater degree of heat than the side of the cylinder which is more remote. In the practice of my invention, I provide means for compensating for such unequal heating effect and thus obtain a cylinder which will be of substantially uniform thickness all around and avoid the formation of other defects in the glass such as ropy structure or a structure not of the highest grade.

In order that my invention may be better understood, I have illustrated it in preferred form in the accompanying drawings wherein—

Figure 1 is a plan view of a deep furnace extension with my improvement applied thereto, and Fig. 2 is a sectional view taken on the line II—II of Figure 1.

I have not shown in these drawings the apparatus employed for raising the bait or for supplying said bait with air which is admitted through the tubular stem thereof or the other mechanical devices for moving the several parts, as such mechanical apparatus is well known in the art and may be of any known or preferred construction.

Referring now more particularly to Figure 2, it will be seen that I have therein

shown a portion of the main chamber of the furnace marked 3 containing a body of molten glass, 4, which extends out into a furnace extension, 5, having in the upper part an aperture in which is placed a top-stone, 6, constructed to be raised and lowered so that it may occupy either the position shown in full lines or the dotted line position indicated also in Figure 2. I have shown the top-stone as square but it could be, if desired, either round or of other configuration, and it is of course provided with suitable means for raising and lowering it and with a cap or cover to close the opening 7 when the stone is raised and the drawing is not taking place. The blow-pipe or bait which I have indicated at 8 may be of any known form and is provided with a tubular handle or stem 9 through which air under pressure is admitted in the usual way, and with suitable raising and lowering mechanism.

In a position partially immersed in the body of glass, 4, and underneath the top-stone, 6, I place what may be called a draw-stone, 10. This draw-stone is preferably square as shown, to prevent it rotating by engagement with the projecting parts 11, and is also preferably wedged in suitable position within the glass by means of the wedges 11'. This construction permits of vertical adjustment of the draw-stone. Within the draw-stone 10 which somewhat resembles a ring in shape, there is a chamber which has on the side away from the main body of the furnace, a wall 12 that is substantially vertical and extends downward through the stone to the bottom thereof as clearly shown in Figure 2. At the opposite side of the chamber within the draw-stone, 10, that is, the side which is nearest the body 3 of the furnace, I provide a sloping wall, 13, which extends a considerable distance beneath the surface of the glass, and is preferably gradually decreased in the amount of its incline until it merges with the vertical wall, 12, on the opposite side, thus producing in general the effect of an offset tubular aperture in the draw-stone indicated in Figure 1.

The operation of my invention is substantially as follows. A cylinder, indicated at 14, being started upward by means of the bait 8 and blow-pipe 9, from the surface of the glass within the draw-stone 10, the effect of the heat on opposite sides of the

draw-stone, which is at a lower temperature near the wall 12 than it is near the wall 13, will tend to automatically shift the cylinder laterally until it reaches a point where 5 such an equilibrium of forces is encountered as will hold it relatively in substantially fixed position with regard to the draw-stone, which normally I have found will be at some place or zone where the wall of the 10 cylinder at the right as indicated at 15 will be in position over the inclined surface 13 which is under the surface of the glass. The square shape of the draw-stone 10 serves to keep the inclined surface 13 on the 15 side nearest the body of the furnace, and the combination of the said inclined surface 13 in that position and the substantially upright surface 12 on the opposite side of the draw-stone, I have found in 20 practice automatically serves to hold the cylinder in its proper position and also avoids the ropy and imperfect effects otherwise produced by other forms of apparatus. The draw-stone 10 is to be made of any 25 suitable material, but I prefer the use of certain kinds of refractory clay ordinarily employed in this class of construction.

Having thus described my invention and illustrated its use, what I claim as new and 30 desire to secure by Letters Patent is the following:

1. In combination in apparatus for drawing glass cylinders, a drawing tank containing a body of glass and heated to a greater 35 extent on one side than on the other, and a draw stone lying in the tank surrounded by the glass thereof, and having an opening therethrough with the wall thereof toward the more highly heated side of the tank inclined to provide a shield projecting beneath a portion of the edge of the cylinder being drawn and having the opposite wall substantially vertical.
2. In combination in apparatus for drawing glass cylinders, a melting tank, a drawing tank communicating freely therewith on its inner side and with the body of glass therein heated from the melting tank, and a draw stone lying in the tank surrounded 40 by the glass thereof and having an opening therethrough with the wall thereof toward the melting tank extended laterally to form a shelf beneath a portion of the periphery of the cylinder being drawn and having the 45 opposite wall of the opening located to the

side of the vertical plane of the remaining portion of the periphery of the cylinder so that such remaining portion is unshielded from the body of glass beneath the draw stone.

3. In combination in apparatus for drawing glass cylinders, a drawing tank containing a body of glass and heated to a greater extent on one side than on the other, and a draw stone lying in the tank surrounded by 60 the glass thereof, and having an opening therethrough with the wall thereof toward the more highly heated side of the tank extended laterally beneath a portion of the edge of the cylinder being drawn and having the opposite wall of the opening lying to one side of the vertical plane of the remaining portion of the periphery of the cylinder so that such remaining portion is unshielded from the body of glass beneath 65 the draw stone.

4. In combination in apparatus for drawing glass cylinders from a body of glass heated to a greater extent on one side than on the other, a draw stone lying partially 70 immersed in the body of glass and having an upwardly extending opening therethrough with the horizontal cross section of such opening at the surface of the glass off center toward the side of the body of glass 75 most highly heated with respect to the horizontal cross section of the opening below the surface of the glass.

5. In combination in apparatus for drawing glass cylinders from a body of glass 80 heated to a greater extent on one side than on the other, a draw stone lying partially immersed in the body of glass and having an upwardly extending opening therethrough with the cross sectional area of the 85 opening at the surface of the glass greater than the cross sectional area of the opening at the lower portion of the draw stone and with the two areas off center with respect to each other, the center of the area at the 90 surface of the glass being nearer to the side of the body of glass most highly heated than the center of the other area.

In testimony whereof I have hereunto signed my name in the presence of the two 95 subscribers witnesses.

HARRY G. SLINGLUFF.
